UNITED STATES PATENT OFFICE.

ERNEST C. KALCY, OF PITTSBURGH, PENNSYLVANIA.

SELF-ELEVATING DEVICE.

1,190,421.

Specification of Letters Patent. Patented July 11, 1916.

Application filed March 14, 1916. Serial No. 84,174.

To all whom it may concern:

Be it known that I, ERNEST C. KALCY, a citizen of the United States, residing at 624 Morewood avenue, Pittsburgh, in the 5 county of Allegheny and State of Pennsylvania, have invented new and useful Improvements in Self-Elevating Devices, of which the following is a specification.

This invention contemplates the provision of a self elevating device, as a substitute for step ladders, and embodies a pair of members in the form of stilts adapted to be secured to the feet of the user, and consisting of adjustable sections, with means 15 for holding the sections fixed relatively in different positions.

The nature and advantages of the invention will be better understood from the following description when read in connection 20 with the accompanying drawings, the invention residing in the construction, combination and arrangement of parts as claimed.

In the drawings forming part of this 25 specification like numerals of reference indicate similar parts in the several views and wherein:

Figure 1 is a view showing the manner of using the invention. Fig. 2 is a side elevation of one of the stilts. Fig. 3 is a vertical transverse sectional view therethrough. Fig. 4 is a sectional view taken on line 4—4 of Fig. 2. Fig. 5 is a similar view taken on line 5—5 of Fig. 2.

35 Before entering into a detail description of what is herein shown, I desire to have it understood that the same is merely illustrative of one embodiment of the invention to which I do not limit myself, and that 40 such changes may be resorted to when desired as fall within the scope of what is claimed.

Referring more particularly to the drawings, the device consists of a pair of stilts 45 indicated at A and B respectively, and as the stilts are identical in construction and operation, a description of one will suffice for both.

Each of the stilts preferably consists of 50 an outer section 10 with which is adjustably associated the section 11. The parts may be of any suitable construction and design, but the section 10 is preferably in the form

of a hollow rectangular frame, while the section 11 is of a similar configuration and 55 mounted for sliding adjustment within the section 10. Fixed to the top 12 of the section 11 is a shoe 13 adapted to receive the foot of the user, and including a buckle 14 and strap 15 through the medium of which 60 the stilt as a whole is secured to the foot. However it is to be understood that various means may be employed for this purpose. The rear wall 16 of the section 11 contacts the corresponding wall of the section 10, 65 while the forward wall 17 of the section 11 is spaced an appreciable distance from the corresponding wall of the section 10. Secured to the wall 17 and arranged within the space between the said section is a sub- 70 substantially channel shaped member 18 co-extensive in length with the length of the wall 17. The channel shaped member is formed to provide a longitudinal series of rack teeth 19 which coöperate with a pawl 75 20 for the purpose of holding the section 11 fixed in its different adjusted positions. It might here be stated that the sections 11 are adjusted singly, that is to say that the weight of the user is supported on one foot 80 while the locking mechanism for the movable section 11 associated with the other foot is released, to permit said section to be elevated by simply lifting the foot the desired distance. The locking mechanism is 85 then restored to normal position to hold the section 11 fixed relatively with its associated section 10, after which the weight of the user is supported on this foot to permit the section 11 of the other stilt to be similarly 90 adjusted. The pawl 20 is not the sole means for holding the section 11 fixed in adjusted position, use being also made of a locking pawl 21 pivoted for lateral adjustment upon an arm 22 projecting from the 95 section 10. The pawl 21 coöperates with a longitudinal series of notches 23 provided in the rear wall of the section 11, and this pawl is normally held in engagement with said notches through the instrumentality of 100 a spring 24 having one end connected with the pawl and its opposite end connected with a bracket 25 projecting from the rear wall of the section 10 as shown.

With a view of simultaneously releasing 105 both the pawls 20 and 21, when it is desired

to effect an adjustment of the section 11, I employ in this particular instance, a substantially U-shaped member which straddles one of the longitudinal edges of the section 10, the parallel limb 27 being journaled in a bearing 28 secured to the exterior of the front wall of the section 10, while the remaining parallel limb 29 of the member is positioned between the forward walls of the 10 respective sections, underlying the pawl 20 in contacting engagement therewith. The limb 27 projects an appreciable distance beyond the bearing 28, and associated with this extremity of the limb 27 is one end of an 15 operating lever 30 which extends vertically into convenient reach of the user of the device. Manifestly when the lever is moved forward, the U-shaped member is rocked upon its limb 27, thereby elevating its limb 20 29 which operates to move the pawl 20 out of engagement with the rack teeth on the section 11. A transverse rod 31 has one terminal connected with the lever 30, while the opposite end of the rod is connected with the 25 pawl 21, and through the instrumentality of this rod the pawl 21 is simultaneously moved with the pawl 20 out of engagement from the notches 23, when the lever 30 is moved forwardly. With the pawls 20 and 30 21 in inoperative position, the section 11 can be easily adjusted vertically by either raising or lowering one foot, while the other foot supports the weight of the user, and subsequent to the proper adjustment of the 35 sections 11, the spring 24 which is under tension when the pawl 21 is in inoperative position, functions to return the parts to normal position upon release of the lever 30, at which time the pawls 20 and 21 engage 40 the sections 11 in a manner to hold the latter fixed relatively with the section 10. The invention is especially advantageous for use by window cleaners, paper hangers, and other partisans who find it necessary to 45 make use of a ladder with their work. Manifestly the sections 11 can be very easily and quickly adjusted, and when fixed in adjusted position provides a very firm support for the user, and at the same time affords 50 considerable use of the limbs which permits the user to move from place to place.

While it is believed that from the foregoing description the nature and advantages of the invention will be readily apparent without requiring a more extended explanation, I desire to have it understood that the component parts of the invention may be constructed from any suitable material, size and design without departing from the 60 spirit of the invention.

What is claimed is:—

1. A self elevating device comprising a pair of stilts, each including a fixed frame-like section and a similar relatively movable 65 telescopic section, and means for holding

said movable section fixed in different adjusted positions.

2. A self elevating device comprising a pair of stilts, each including telescopic frame-like sections, one of which is capable of adjustment with respect to the other, means carried by one of said sections for connecting the stilt with the foot of the user, and means for holding said sections fixed relatively. 75

3. A self elevating device comprising a pair of stilts, each including telescopic frame-like sections, one of which is capable of adjustment with respect to the other, means for locking the movable section in 80 adjusted position, and means carried by said section for connecting the same to the foot of the user whereby the section is adapted to be adjusted by the raising or lowering of the foot, subsequent to the release of said 85 means.

4. A self elevating device comprising a pair of stilts, each including a fixed frame-like section and a similar relatively movable telescopic section, means carried by the 90 movable section for connecting the latter to the foot of the user for adjustment therewith, pawl and ratchet mechanism for holding said movable section fixed in adjusted position, and means for controlling said 95 mechanism to permit of the adjustment of said section.

5. A self elevating device comprising a pair of stilts, each including a fixed frame-like section, and a similar section slidably 100 fitted within the fixed section, means for connecting the movable section to the foot of the user for adjustment therewith, and means for holding said movable section fixed in adjusted position. 105

6. A self elevating device comprising a pair of stilts, each including an outer frame like section, and an inner frame like section 110 slidably adjustable within the outer section, said inner section having spaced series of notches, a pawl adapted to coöperate with each series of notches, said pawls being pivoted upon the outer section, and means for simultaneously effecting a release of said pawls to permit of an adjustment of said inner section. 115

7. A self elevating device comprising a pair of stilts, each including an outer frame like section, and an inner frame like section 120 slidably adjustable within the outer section, said inner section having spaced series of notches, a pawl adapted to coöperate with each series of notches, and mechanism for simultaneously effecting a release of said pawls including a lever disposed in convenient reach of the user. 125

8. A self elevating device comprising a pair of stilts, each including an outer frame like section, and an inner frame like section 130 slidably adjustable within the outer section,

said inner section having spaced series of notches, a pawl adapted to coöperate with each series of notches, said pawls being pivoted to the outer section, a yoke mounted 5 on said section for rocking movement and engaging one of said pawls, a lever for operating said yoke to release said pawl, and a connection between the lever and the other

pawl to simultaneously effect a release of both of said pawls. 10

In testimony whereof I affix my signature in presence of two witnesses.

ERNEST C. KALCY.
